REFRIGERATED DISPLAY CASE

John R. Caulk, Jr., Ladue, and Russell E. Davis,
St. Louis, Mo., assignors to Hussman-Ligonier
Company, St. Louis, Mo., a corporation of
Missouri

Application November 28, 1941, Serial No. 420,798

3 Claims. (Cl. 62—89.5)

Our invention relates to refrigerated display cases, particularly those of the so-called open type, where the merchandise is exposed in an open bin which is continuously refrigerated.

The invention has for its principal objects to provide an efficient, simple and compact cooling refrigerating system for display cases of this type.

The invention consists principally in a refrigerated display case of this type wherein the cooled air is propelled upwardly through a refrigerating flue and is discharged above the level of the merchandise, over which it flows to a return duct, where it is again passed through the refrigerating and merchandise cooling cycle. The invention further consists in the refrigerated display case and in the refrigerating method, in the steps and in the parts and combinations and arrangements of parts hereinafter described and claimed.

In the accompanying drawings,

Fig. 1 is a top plan view of a refrigerated display case embodying our invention, a portion of the top of the case being broken away,

Fig. 2 is a front elevation,

Fig. 3 is a cross-sectional view, on an enlarged scale on the line 3—3 in Fig. 2,

Fig. 4 is a longitudinal sectional view on the line 4—4 in Fig. 1,

Fig. 5 is a horizontal sectional view on the line 5—5 in Fig. 2,

Fig. 6 is a horizontal sectional view on the line 6—6 in Fig. 2,

Fig. 7 is a top plan view, on an enlarged scale, of a deflector for deflecting and baffling the current of air on its way to the cooling flue,

Fig. 8 is a front elevation of said deflector,

Fig. 9 is a side or end elevation thereof,

Fig. 10 is a perspective view of the front air baffle in the path of the return air on its way from the intake duct to the fan; and

Fig. 11 is a perspective view of one of the supporting members for the bottom of the merchandise bin.

The refrigerated display case has a base 1, a low front wall 2, a high back wall 3, a top 4 extending from the back wall over a portion of the merchandise bin to form a hood or partial cover therefor, and end walls 5. Said parts are all of any suitable construction, including insulated body portions 6 and ornamental trim or cover portions 7 of porcelain metal or the like. The front wall 2 extends slightly above the bottom 8 of the merchandise bin (which is made up of parts hereinafter described) and preferably has a glass wall or series of panels 9 extending along its top. The corner portions 10 of the end walls

5 slope downwardly from the cover 4 to a point just above the level of the top of the glass wall 9. Fluorescent or other lights 11 are arranged at the front of the cover 4 or top so as to illuminate merchandise in the display bin.

Extending from end to end of the case and resting on supporting flanges 12 on the end walls 5, is a supporting strip 13 having base portions 14, an upstanding lip 15 along its rear edge and an upstanding rib 16. Extending from end to end of the case near the front thereof and resting on the support 12, for the rear strip 13, is a supporting strip 17 having base flanges 18 and an upstanding central rib 19 of the same height as that 16 of the rear strip 13. Mounted on the front base flange 18 of said strip 17 is a horizontal flange 20 of an angular member whose vertical flange 21 has an inwardly bent lip or bead 22. This vertical flange 21 is spaced away from the front wall 2 of the case to form an air intake or duct 23 which will be hereinafter pointed out. Extending from end to end of the case at about the middle is a supporting strip 24, similar to the front strip 17, having base flanges 25 and an upstanding central rib 26 of the same height as those of the front and rear supporting strips. The spaces between the ribs of the front 17, rear 13 and middle supporting strips 24 are filled by sheets 27 resting on the base flanges of said strips. The above described parts constitute a horizontal partition which forms the bottom 8 of the merchandise bin.

Extending from front to rear of the case, at the middle thereof, is a support 28 of inverted channel section which supports the front strip 17, middle strip 24 and rear strip 13 and which has its ends resting on brackets 29 secured to the front and rear walls, respectively.

Secured to the rear wall 3, as by screws 30 mounted in countersinks 31, are spacer blocks 32. Secured to these spacers blocks 32, as by screws 33, is a sheet or wall 34 of insulating material that extends from end to end of the case and has its lower edge resting on the rear supporting strip 13 against the rear lip 15 thereof. Said wall 34 and the rear wall 3 of the box form a flue 35 in which is disposed a refrigerating device 36, preferably comprising a plurality of coils 37 extending from end to end of the case and having suitable fins 38 thereon. The top of the wall 34, that is, the outlet of the cold air discharged from the flue 35, is above the level of the merchandise support.

Preferably the merchandise support is in the form of a stepped base 39, the top step 40 being

below the level of the flue outlet and the bottom step 41 being above the base 8 of the display chamber. As indicated in dotted lines in Fig. 3, the merchandise support may be in the form of a simple shelf 38A or screen resting on the ribs of the supporting strips 13, 17 and 24.

As the air must move upwardly through the cooling cycle, it is necessary to create a forced circulation. A fan 42 for this purpose is mounted over an opening 43 in a vertical partition wall 44 that extends from end to end of the case, dividing into a front chamber 45 and a rear chamber 46, the space between the bottom 1 of the case and the bottom 8 of the display bin. The fan 42 and the motor 42a therefor are mounted on a suitable frame 42b that is secured to said partition wall 44. The fan 42 is disposed so as to cause air to move from the front chamber 45 into the rear chamber 46 and thence upwardly through the cooling flue 35 in which is disposed the refrigerating device 36. A baffle or deflector 47 is mounted in front of the fan 42, in the front or air intake chamber 45, said baffle 47 being preferably a simple vertical strip having a bottom flange 48 secured to the bottom of the case. A rear baffle or deflector 49 is placed in the rear compartment 46 between the fan 42 and the cooling flue 35. Said rear deflector includes a central strip 50 arranged at an angle, rearwardly bent body members 51 and reversely or forwardly rebent lower wing members 52 to which are secured angle brackets 53 having bottom members 54 secured to the bottom of the case. An angle bracket 55 secured to the central strip extends into said channel support 28 and is suitably secured to the base thereof.

As appears from the arrows, cold air discharged from the top of the flue 35, flows downwardly over the merchandise 56 arranged in the bin, preferably on the steps. The cold air tends to hug the merchandise and cascade down the steps after the fashion of a waterfall. At the front of the case, the air now warmed by passing over the merchandise passes into the front chamber through the intake duct 23, being drawn thereto by the action of the constantly rotating fan 42. The air flow is equalized along the entire intake duct 23 by means of the front baffle member 47 and after being discharged by the fan 42 into the rear chamber 46 the air is again deflected or baffled by means of the rear deflector 49. By reason of the large size of the rear chamber, the air moves to the flue 35 and through the flue rather slowly. The deflector 49 and the weight of cold air cause equal distribution of air from entire length of discharge flue 35. The outlet of the flue is above the level of the top of the wall 9 as well as above the merchandise support. This permits merchandise to be displayed above the top of the wall 9.

While the refrigerating mechanism is shown as being mounted in the flue 35, it may be mounted anywhere in the system between the inlet duct 21 and the outlet of the flue 35.

The above arrangement produces a continuously acting refrigerating cycle, the cold air moving in a slow and gentle current. The refrigerating mechanism operates continuously, except for an

occasional interruption to permit defrosting or when the minimum desired display temperature is reached. The degree of cooling of the air may be regulated to suit the requirements of the particular merchandise being displayed. The display case is particularly adapted for use in displaying meats and dairy products, but may be used with vegetables and produce.

Obviously numerous changes may be made without departing from the invention and we do not wish to be limited to the precise construction shown.

What we claim is:

1. In a refrigerated display case having a base, a top, a rear wall, a front wall and end walls, a horizontal partition extending from end to end of the case with its respective side edges spaced from said front and rear walls, a vertical partition spaced from said rear wall, with its lower edge resting on said horizontal partition and its upper edge spaced below said top, a refrigerating device in the flue formed by said rear wall and said vertical partition, a lower vertical partition extending from end to end of said case and from said base to said horizontal partition, a fan disposed over an opening provided therefor in said lower vertical partition and arranged to blow air therethrough to create a circulation of air upwardly through said flue and said refrigerating device, and a baffle disposed forwardly of said fan.

2. In a refrigerated display case having a base, a top, a rear wall, a front wall and end walls, a horizontal partition extending from end to end of the case with its respective side edges spaced from said front and rear walls, a vertical partition spaced from said rear wall, with its lower edge resting on said horizontal partition and its upper edge spaced below said top, a refrigerating device, a lower vertical partition extending from end to end of said case and from said base to said horizontal partition, a fan disposed over an opening provided therefor in said lower vertical partition and arranged to blow air therethrough to create a circulation of air through said refrigerating device and upwardly through the flue formed by said rear wall and said vertical partition, and a baffle disposed rearwardly of said fan.

3. In a refrigerated display case having a base, a top, a rear wall, a front wall and end walls, a horizontal partition extending from end to end of the case with its respective side edges spaced from said front and rear walls, a vertical partition spaced from said rear wall, with its lower edge resting on said horizontal partition and its upper edge spaced below said top, a refrigerating device in the flue formed by said rear wall and said vertical partition, a lower vertical partition extending from end to end of said case and from said base to said horizontal partition, a fan disposed over an opening provided therefor in said lower vertical partition and arranged to blow air therethrough to create a circulation of air upwardly through said flue and said refrigerating device, and baffles disposed forwardly and rearwardly of said fan, respectively.

JOHN R. CAULK, JR.
RUSSELL E. DAVIS.
